UNITED STATES PATENT OFFICE

BENJAMIN KOLBER, OF PHILADELPHIA, PENNSYLVANIA

ONE-PIECE DOUBLE-COMPARTMENT TOILET CABINET

Application filed November 27, 1929. Serial No. 410,150.

The present invention relates to an improved one piece double compartment cabinet particularly adapted for use in toilets for toilet articles, shaving paraphernalia and the like, and an essential purpose of the invention is to provide a cabinet of this kind especially adapted for shaving purposes.

One of the features of the construction is the fact that the cabinet is made in one piece, either pressed metal, cast or die formed.

Another feature of construction comprises the formation of a cabinet having double compartments, a large compartment at the top having a closure therefor, and a smaller open compartment at the bottom, the construction of the cabinet being such that the two compartments may be formed at the time the cabinet is formed.

Another feature comprises a counter-sunk opening in the top of the cabinet to receive a socketed element for the reception of the threaded plug and of an incandescent lamp bulb, the counter-sunk opening and the socketed element being so disposed as to direct the rays of light downwardly toward a person standing in front of the cabinet shaving or otherwise using a mirror in the door or closure for the main compartment.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

40 Figure 1 is a view in perspective of the improved cabinet constructed in accordance of the invention.

Figure 2 is a vertical sectional view on line 2—2 of Figure 1.

45 Figure 3 is a perspective view of the cabinet showing the rear face thereof, illustrating part of the cabinet broken away to better illustrate the construction.

50 Figure 4 is a sectional view on line 4—4 of Figure 3.

Referring to the drawings, 1 identifies the cabinet as a whole, and disregarding the door or closure 2 (which is hinged at 3 and adapted for closing the main compartment 4 of the cabinet) it is constructed in one piece, either 55 pressed metal, cast or possibly die stamped.

The cabinet has a formed compartment 5 spaced a short distance below the major or main compartment. The main compartment 4 is designed to receive various toilet articles, 60 such as shaving and facial creams, tooth pastes, shampoos and the like, shaving paraphernalia and medicines, there being a plurality of shelves 6 supported in any suitable manner, possibly as shown at 7, to support 65 such articles.

The lower open compartment has a bottom 8, which may support a shaving mug and brush, razor or any other article which may be adapted for ordinary use.

70 As previously stated the cabinet may be made of pressed metal, cast or die stamped, and the upper compartment is formed from the metal, that is it is counter-sunk from the metal, or rather from the fact of the cabinet, 75 in such a manner as to provide for a marginal flange portion 9, said flange portion 9 extending downwardly on the sides of the cabinet and merge into ornamental curved portions 10, which integrally merge into the bottom or shelf 8 of the cabinet, the lower portion of the shelf or bottom 8 also has a flange, which is really a part of the marginal flange 9.

75 The flange 9 merges into an ornamental 85 flange portion 11 at the top of the cabinet, which ornamental portion is of a curved contour or centrally bulged, which merges into the downwardly and laterally curved parts at the upper end of the flange 9. This ornamental flange 11 or extension has a counter-sunk flanged opening 12, the flange of which is tapered as identified at 13, while a portion of the flange merges into a cylindrical part 14 which receives securely a socketed element 90 15, which is adapted to receive the plug end 16 of an incandescent lamp or bulb 17. The interior of the counter-sunk opening 12 for the bulb or lamp 17 acts as a reflector, and due to the counter-sunk opening 12 being in- 100

clined upwardly and on account of a semi-marginal reflecting flange 18 the light rays from the bulb or lamp are directed downwardly toward a person who may be standing in front of a mirror 19 mounted in the door or closure 2. In the present instance the door 2 has a knob or handle 20, by which the door may be operated.

The invention having been set forth, what is claimed is:

- 10 1. A one piece toilet cabinet formed from metal, said cabinet comprising a body having a marginal angular flange and provided with a base shelf, which merges into the flange, and the lower portions of the flange having curved parts integrally connecting with the bottom shelf, said cabinet having an upper dominant and a lower auxiliary open compartment, a closure for the upper dominant compartment, said flange merging integrally with a flanged extension at the top of the cabinet, said flanged extension having a counter-sunk flanged opening for the reception of an electric lamp or bulb.
- 15 2. A one piece toilet cabinet formed from metal, said cabinet comprising a body having a marginal angular flange and provided with a base shelf, which merges into the flange, and the lower portions of the flange having curved parts integrally connecting with the bottom shelf, said cabinet having an upper dominant and a lower auxiliary open compartment, a closure for the upper dominant compartment, said flange merging integrally with a flanged extension at the top of the cabinet, said flanged extension having a counter-sunk flanged opening for the reception of an electric lamp or bulb, said flanged counter-sunk opening having its axis inclined
- 20 30 35 40 45 downwardly and forwardly thereby correspondingly directing the light rays toward and upon the head of a person in front of the cabinet.

In testimony whereof he affixes his signature.

BENJAMIN KOLBER.
